UNITED STATES PATENT OFFICE.

CHRISTIAN C. HILL, OF CHICAGO, ILLINOIS, ASSIGNOR TO THE MONITOR WORKS, OF BELOIT, WISCONSIN.

SPUR-WHEEL FENCE-WIRE TWISTING AND SPOOLING MACHINE.

SPECIFICATION forming part of Letters Patent No. 373,457, dated November 22, 1887.

Application filed May 3, 1887. Serial No. 236,004. (No model.)

To all whom it may concern:

Be it known that I, CHRISTIAN C. HILL, a citizen of the United States, residing in Chicago, in the county of Cook and State of Illinois, have invented a new and useful Improvement in Spur-Wheel Fence-Wire Twisting and Spooling Machines, of which the following is a specification.

The object of my invention is to provide a machine of a simple and cheap construction for twisting and spooling spur-wheel fence-wires or other filaments.

My invention consists in the novel devices and novel combinations of devices herein shown and described, and more particularly pointed out in the claims.

In the accompanying drawings, which form a part of this specification, and in which similar letters of reference indicate like parts, Figure 1 is a plan view of a device embodying my invention. Fig. 2 is a side elevation. Figs. 3 and 4 are central longitudinal sections showing the spindles or bearings of the twister-frame, and Fig. 5 shows a modification.

In said drawings, A A represent the frame or standards upon which the twister-frame B is mounted or journaled. The twister-frame B is cast with a large hollow spindle, B', at one end, having a channel or groove, b, for the bearings b' b' to fit in. The cap or upper bearing-block b' is preferably of wood, and is secured in place by long bolts b². Through the opening in this hollow spindle B' the wire or wires to be spooled or twisted and spooled pass, and the opening should be large enough to permit the wire or wires to be inclined by the guiding device from one end of the spool to the other without causing the wires or the spur-wheels thereon to strike against the inside of said hollow spindle. In practice, I ordinarily make the hollow spindle about eight inches in diameter for twisting and spooling spur-wheel fencing or barbed wires, the spools for which are ordinarily about one foot in length. The size of the hollow spindle may, however, be greatly varied. The twister-frame is also provided or cast with a smaller hollow spindle, B', at its opposite end, having collars b³ b³, between which fit the anti-friction bearing-wheels b⁴ b⁴, which are journaled upon

suitable studs, a a, secured to the frame or standard A. A strap, a', secured to the frame, serves to hold the spindle in place on its anti-friction wheels.

C is a spindle fitting loosely in the hollow spindle B', having a driving-gear, c, secured on its inner end, and a pulley, C', on its outer end.

C' is a friction-clamp attached to a bracket, C³, on the frame, and consisting, preferably, of a pair of wooden blocks secured together at one end by an adjusting-screw or threaded bolt, C⁴.

D is a revolving spool-shaft upon which the spool is supported. This shaft is rotated by means of a bevel-gear, d, thereon, which meshes with a bevel-gear, d', on the shaft d², journaled on the spool-frame, and which shaft has a spur-gear, d³, that meshes with an intermediate gear, d⁴, which is driven by the gear c on the end of the shaft C.

E is the vibrating guide-arm, having a yoke or forked end e e, pivoted to the large hollow spindle B' of the frame B. This vibrating arm carries on its free end a pair of skeleton guide-rolls, F F, between which the wires pass and are guided to the spool. The arm E is vibrated back and forth from one end of the spool to the other by means of a heart-cam, G, journaled on the frame B, which operates a pivoted lever, g, connected by a pivoted link, g', with a projecting arm or lever, g², on the vibrating arm. The heart-cam wheel G is intermittently rotated from the spool-shaft by means of what is known as a "Geneva stop" or "gear"—that is to say, a cam-wheel, H, having a pin, h, on the spool-shaft D, which engages a cam, H', cast integral with the heart-cam G, and which cam H' has notches h', that engage the pin h. The rotation of the spool-shaft transmits an intermittent motion to the heart-cam wheel, and the heart-cam transmits a rectilinear motion to the link g', and this link gives a vibratory movement back and forth to the arm E and the guide-rolls F F, mounted thereon.

The spool-shaft revolves whenever the tension on the strand being wound around the spool is not sufficient to overcome the friction of the clamp C' on the friction-wheel C'. When the tension on the strand is the greater, the wheel C' of course turns in the friction-clamp.

The spool is inserted in the usual manner by withdrawing or partially withdrawing the shaft D from the frame B, then inserting the spool, and replacing the shaft through the 5 spool.

When it is desired to wind the wire upon the spool without twisting the same, the chain K is removed from the sprocket-wheels K' K², by which motion is communicated to the twister-frame from the driving-shaft K³, and the pulley K⁴ is belted directly to the pulley C', the friction-clamp of course being loosened or removed.

In the modification shown in Fig. 5 the bearing for the spindle at the driving end of the twister-frame is of the ordinary form, but connected by a horizontal pivot, x, to the standard A, so that the bearing may adjust itself to the axis of the twister. As no rigid 20 and unyielding frame is employed to support the twister, the frame consisting simply of a pair of standards the feet of which are screwed or otherwise secured to the floor, and unconnected together except by the driving-shaft 25 and twister-frame, the bearings might not always properly align each other if fixed rigidly to the standards. While the anti-friction bearing, as shown in Figs. 1 and 2, is employed, there is no necessity for pivoting it.

While the twister and spooler, as shown in 30 the drawings, is specially designed for twisting and spooling fence-wires, my invention may be used for twisting and spooling other strands or filaments.

The large spindle B' or its collar b⁵ turns on 35 the anti-friction bearing-wheels b⁶ b⁶, which support the weight of the twister, while the blocks b' b', fitting on the groove b, serve to keep the twister-frame in place.

I claim—

1. The combination, with twister-frame B, of spool-shaft D, vibrating guide-arm E, having yoke or forked end e e, pivoted to said twister-frame, and provided with a projecting arm, g², link g', a heart-cam, G, and a Geneva-gear movement for intermittently operating said heart-cam from said spool-shaft, and means to rotate the spool-shaft, substantially as specified. 45

2. The combination of spool-shaft D, pivoted vibrating arm E, link g', pivoted to said arm, 50 lever g, cam G, cam H', having notches h', and cam H, having pin h, substantially as specified.

CHRISTIAN C. HILL.
